UNITED STATES PATENT OFFICE.

LOUIS B. HASBROUCK, OF ELMIRA, NEW YORK, ASSIGNOR TO ECLIPSE TEXTILE DEVICES, INC., OF ELMIRA HEIGHTS, NEW YORK, A CORPORATION OF NEW YORK.

YARN CLEANER.

Application filed January 3, 1924. Serial No. 684,132.

To all whom it may concern:

Be it known that I, LOUIS B. HASBROUCK, a citizen of the United States, residing at Elmira, in the county of Chemung and State of New York, have invented certain new and useful Improvements in Yarn Cleaners, fully described and represented in the following specification and the accompanying drawing, forming a part of the same.

10 This invention relates to yarn cleaners and aims to provide a simple and effective device for removing impurities of all sorts from a traveling yarn. An object of the invention is to provide a yarn cleaner in which 15 all impurities removed from the yarn and any fibrous matter detached with them are continuously discharged from the cleaner without the use of any mechanically driven parts. A further object of the invention is 20 to provide a yarn cleaner which will place the yarn under any desired tension so that no tension device need be used in the cleaner. A still further object is to provide a cleaner which will automatically adjust itself for 25 operation upon a yarn of any size.

A yarn cleaner embodying the invention in a form which I have found satisfactory includes a blade providing a scraping edge across which the yarn is drawn, and a 30 movable member having a surface opposed to the scraping edge, resting on the yarn, and holding the yarn in firm contact with the edge, and a surface opposed to one side of the blade and cooperating therewith to 35 confine the particles and fibrous matter detached from the yarn. The movable member is continuously moved, preferably by the travel of the yarn, in such manner that it carries the particles of fibrous matter detached from the yarn away from the line of 40 travel of the yarn and continuously discharges them from the cleaner.

The invention may best be understood from a detailed description of a specific yarn cleaner embodying it, such as that shown in the accompanying drawing, in which:

Fig. 1 is a view of the cleaner looking in the direction of the arrow 1 in Fig. 4;

Fig. 2 is a view similar to Fig. 1, but sectioned on the line 2—2 of Fig. 3;

Fig. 3 is a view of the cleaner looking in the direction of the arrow 3 in Fig. 4; and

Fig. 4 is an enlarged transverse section of the cleaner taken on the line 4—4 of Fig. 1.

The cleaner illustrated has a supporting plate 10 provided with a bracket 11. In order that the plate 10 may be tipped laterally at any desired angle to the horizontal, the bracket 11 is provided with a pin 12 projecting at one end of the plate 10 and adjustably secured by means of a set screw 13 in a socket 14 at the outer end of a supporting arm 15. The traveling yarn A to be cleaned is guided across the plate 10 in a longitudinal direction by a front thread guide 16 and a rear thread guide 17. Between these guides is mounted a cleaning unit consisting of a fixed member 20 and a rotatable member 30.

The fixed member 20 has the form of a blade projecting perpendicularly outward from the surface of the plate 10. It is secured to the plate by screws 21 passing through tabs 22 at the ends of the blade. The front end portion 23 and the rear end portion 24 of the blade are straight, while the middle portion 25 of the blade is arc-shaped. The blade 20 is bevelled at 26 on its rear or outer side so as to provide it with an acute scraping edge 27.

The rotary member 30 is mounted on a depending pivot pin 31 which is fixed in a bracket 32 secured to the plate 10. The axis of this pin is slightly nearer the middle portion 25 of the blade 20 than is the center of the arc on which this portion of the blade lies.

The shape of the rotary member 30 is best shown in Fig. 4. Although this member is preferably made of a single piece, it may for convenience in description be regarded as consisting of: a disc 33 having a flat surface 34 opposed to the edge 27 of the blade 20; a drum 35 of less diameter than the disc and having a cylindrical surface 36 opposed to the inner or front side 28 of the blade 20; and a sleeve 37 which cooperates with a central hole through the disc and drum in providing the rotary member with a long bearing on the pin 31. The disc 33 has a bevelled surface 38 at the periphery of its flat surface 34. The drum 35 has a radius less than that of the arc-shaped middle portion of the blade 20, and is spaced a short distance from the central part of the blade, so that the cylindrical surface 36 of the drum and the inner side 28 of the blade 20 enclose two wedge-shaped spaces 40, 42 connected by a narrow passage 41.

The operation of the cleaner which has been described is as follows:—The device is threaded by dropping a yarn A into the recesses in the front and rear guides 16 and 17. 5 As soon as the pull is applied to the yarn to draw it forward through the cleaner, the yarn is brought against the bevelled edge 26 of the blade 20 and the bevelled edge 38 of the disc 33 and raises the rotary member 30 10 sufficiently to permit the yarn to enter between the scraping edge 27 of the blade 20 and the flat surface 34 of the disc 33. The guides 16, 17 are so positioned that after the yarn has slipped under the surface 34 it 15 comes in contact with the cylindrical surface 36 of the drum 35 at substantially the same point in its travel as that at which it crosses the scraping edge 27, and is deflected slightly from a straight line of travel at this 20 point so that it contacts firmly with the cylindrical surface. The flat surface 34 is urged toward the scraping edge 27 by the weight of the rotary member 30 so that the 25 yarn is held in firm contact both with the edge and with this surface.

As the yarn is drawn across the scraping edge 27 in firm contact therewith, the edge serves to scrape from the yarn small particles and impurities of all sorts. Such particles and any fibrous matter scraped off with them are confined in the wedge-shaped space 40 between the cylindrical surface 36 of the drum 35 and the front part of the inner surface 28 of the blade 20. The friction 30 between the yarn and the surfaces 34 and 36 causes a continuous rotation of the member 30. In this rotation, the portion of the surface 34 in contact with the yarn is continuously moved in a direction approximately 35 longitudinal of the middle portion of the blade 20, and, in this movement, carries away from the yarn any particles and fibrous matter which may become lodged between the surface 34 and the scraping edge 27. 40 The movement of the cylindrical surface 36, in the rotation of the member 30, carries the particles and fibrous matter confined in the wedge-shaped space 40 through the narrow passage 41 between the central portion of 45 the blade and the drum 35 so that such matter is continuously discharged through the wedge-shaped space 42 between the drum 35 and the rear part 24 of the blade. Any of 50 the particles of fibrous matter which may adhere to the surface 36 are loosened from this surface by a fixed scraper 45, whose end 55 is just out of contact with the surface 36, and are, therefore, continuously discharged from the cleaner.

60 The firmness of the contact of the scraping edge 27 with the yarn and the tension applied to the yarn may be regulated by changing the angle of the plate 10 to the horizontal. In this manner the pressure on 65 the yarn is adjusted so that the yarn con-

tacts with the edge 27 as firmly as possible without placing the yarn under a tension great enough to cause it to break.

While a single cleaning unit has been illustrated and described, it will be understood 70 that, if desired, a plurality of such units may be used, and that the units may be mounted on a single supporting plate so as to operate on the traveling yarn in series.

Many changes may be made in the form 75 and arrangement of the parts of the specific embodiment illustrated without departing from my invention. I wish it understood, therefore, that the invention is not confined to particular features of the embodiment shown, except in so far as is specified in the 80 claims which follow. Furthermore, certain features of the yarn cleaner described form the subject matter of claims in my copending application filed January 8, 1924, Serial 85 No. 684,131, and are therefore, not claimed in this application.

What I claim is:

1. A yarn cleaner for removing particles 90 from a traveling yarn, comprising a member providing a scraping edge across which the yarn is drawn, and a member providing a smooth surface opposite said edge and in contact with the yarn, one of said members being so moved that the part thereof 95 in contact with the yarn travels longitudinally of the scraping edge to carry away particles and fibrous matter scraped from the yarn by the edge.

2. A yarn cleaner for removing particles 100 from a traveling yarn, comprising a member providing a scraping edge across which the yarn is drawn, and a member providing a smooth surface opposed to said edge and separated therefrom by a distance less than the normal diameter of the yarn so that the 105 yarn is held in firm contact with the scraping edge and with said surface, one of said members being continuously so moved that the part thereof in contact with the yarn travels in a direction longitudinal of the scraping edge to carry off particles and fibrous matter scraped from the yarn by the edge.

3. A yarn cleaner for removing particles 110 from a traveling yarn, comprising a member providing a scraping edge across which the yarn is drawn, a member providing a smooth surface opposed to said scraping edge, one of said members being continuously 115 so moved that the part thereof in contact with the yarn travels in a direction longitudinal of the scraping edge, and means for yieldably urging said members 120 toward each other so that the yarn is held in firm contact with the scraping edge and the smooth surface.

4. A yarn cleaner for removing particles 125 from a traveling yarn, comprising a member providing a scraping edge, a member 130

providing a flat surface opposed to said scraping edge, means for guiding the traveling yarn between the scraping edge and the smooth surface in a direction oblique to the scraping edge, and a mounting for one of said members permitting said member so to move under the effect of the friction between it and the yarn that the part thereof in contact with the yarn travels in a direction longitudinal of the scraping edge.

5. A yarn cleaner for removing particles from a traveling yarn, comprising a member providing an arc-shaped scraping edge, a member providing a smooth surface opposed to said scraping edge, means for guiding the traveling yarn between the scraping edge and the smooth surface in a direction oblique to the scraping edge, and a mounting for one of said members permitting rotation thereof about an axis so positioned with respect to the scraping edge that the portion of the flat surface in contact with the yarn moves longitudinally of the portion of the edge in contact with the yarn.

6. A yarn cleaner for removing particles from a traveling yarn, comprising a member providing a scraping edge across which the yarn is drawn, and a member providing a smooth surface opposed to said scraping edge in contact with the yarn and continuously so moved that the part thereof in contact with the yarn travels in a direction longitudinal of the scraping edge to carry away particles and fibrous matters scraped from the yarn by the edge.

7. A yarn cleaner for removing particles from a traveling yarn, comprising a member providing a scraping edge across which the yarn is drawn, and a member providing a smooth surface which is opposed to said scraping edge, separated therefrom by a distance less than the normal diameter of the yarn, and is continuously so moved that the part thereof in contact with the yarn travels in a direction longitudinal of the scraping edge to carry away particles and fibrous matter scraped from the yarn by the edge.

8. A yarn cleaner for removing particles from a traveling yarn, comprising a member providing a scraping edge across which the yarn is drawn, a member providing a smooth surface opposed to said scraping edge and continuously so moved that the part thereof in contact with the yarn travels in a direction longitudinal of the scraping edge, and means for yieldably urging said members toward each other so that the yarn is held surface opposed to said scraping edge and the smooth surface.

9. A yarn cleaner for removing particles from a traveling yarn, comprising a member providing a scraping edge, a member providing a smooth surface opposed to said

scraping edge and in contact with the yarn, and a mounting for said second member arranged to permit such member so to move under the effect of the friction between the yarn and the smooth surface of such member that the portion of said surface in contact with the yarn travels in a direction longitudinal of the scraping edge.

10. A yarn cleaner for removing particles from a traveling yarn, comprising a member providing an arc-shaped scraping edge, means for guiding the traveling yarn across said scraping edge in a direction oblique thereto, a member providing a smooth surface opposed to said scraping edge, and in contact with the yarn, and a mounting for said second member arranged to permit rotation thereof about an axis so positioned with respect to the scraping edge that the portion of the flat surface in contact with the yarn moves longitudinally of the portion of the edge in contact with the yarn.

11. In a yarn cleaner for removing particles from a traveling yarn, the combination of means providing smooth surfaces positioned to include an enclosed wedge-shaped space along one side of which the yarn is drawn, and means for continuously ejecting from said space particles removed from the yarn.

12. A yarn cleaner for removing particles from a traveling yarn, comprising a rotatably mounted member having a cylindrical surface, a blade having a smooth surface opposed to said cylindrical surface and positioned to include therewith a wedge-shaped space, and means for guiding the yarn across said cylindrical surface in a direction perpendicular to its axis and along one side of said wedge-shaped space.

13. A yarn cleaner for removing particles from a traveling yarn, comprising a blade having a scraping edge across which the yarn is drawn, and means cooperating with the front side of said blade to confine particles and fibrous matter scraped from the yarn by said edge and to continuously eject such particles and fibrous matter from the cleaner.

14. A yarn cleaner for removing particles from a traveling yarn, comprising a blade having a scraping edge across which the yarn is drawn, and means cooperating with the front side of the blade to confine particles and fibrous matter scraped from the yarn by the edge, such means being continuously moved by the yarn to eject the confined particles and fibrous matter from the cleaner.

15. A yarn cleaner for removing particles from a traveling yarn, comprising a blade having a scraping edge across which the yarn is drawn, a member having a surface opposed to said scraping edge, contacting with the yarn, and holding the yarn in firm

contact with the edge, and a surface opposed to the front side of the blade and co-operating therewith to confine the particles and fibrous matter scraped from the yarn, said member being continuously moved to eject the confined particles and fibrous matter from the cleaner.

16. A yarn cleaner, comprising a blade having a scraping edge across which the yarn is drawn, a rotatably mounted member having a flat surface opposed to the scraping edge and a cylindrical surface opposed to the front side of the blade, and means for guiding the traveling yarn between the scraping edge of the blade and the flat surface and against the cylindrical surface.

17. A yarn cleaner for removing particles from a traveling yarn, comprising a blade having a scraping edge, means for guiding the yarn across said edge in a direction oblique thereto, and a rotatably and slidably mounted member having a flat surface opposed to said edge and resting on the yarn and a cylindrical surface opposed to the front side of the blade and lying close to the blade at the point at which the yarn crosses the edge of the blade.

18. A yarn cleaner for removing particles

from a traveling yarn, comprising an arc-shaped blade having a scraping edge and a concave cylindrically curved front surface, and a rotatably and slidably mounted member comprising a drum of radius less than that of the blade and spaced a short distance from the front surface of the blade at the central part thereof and a disc of radius larger than that of the blade having a flat surface opposed to the edge of the blade and resting on the yarn.

19. A yarn cleaner for removing particles from a traveling yarn, comprising a member having a smooth front surface, a rotatably mounted drum having a cylindrical surface cooperating with said front surface to include two wedge-shaped spaces connected by a narrow passage, a fixed scraper having its end located close to the cylindrical surface of said drum at a distance from said blade, and means for guiding the traveling yarn along the side of one of said wedge-shaped spaces and in contact with the cylindrical surface of the drum.

In testimony whereof I have hereunto set my hand.

LOUIS B. HASBROUCK.
